REGULATOR FOR TIME-INSTRUMENTS

Dudley S. Ingraham, Bristol, Conn., assignor to
 The E. Ingraham Company, Bristol, Conn., a
 corporation

Application January 6, 1934, Serial No. 705,527

4 Claims. (Cl. 58—113)

This invention relates to improvements in time-instruments, and more particularly to improvements in regulators for time-instruments.

Heretofore, in time-instruments of the marine or lever-movement type, in which the regulator has an arm or finger provided with a slot for adjustably engaging the hairspring, there has been considerable trouble from the hairspring fouling or becoming caught over the regulator-arm when the time-instrument has been subjected to severe shocks or jars which cause the hairspring to surge widely out of its normal position and have one or more of its coils become fouled or hooked over the regulator-arm, thereby causing the time-instrument to become so inaccurate in its timekeeping qualities as to be substantially useless until the hairspring has been returned to its normal position. Many attempts have been made in the long history of the time-instrument art to overcome this difficulty and, while a certain degree of success has been attained, up to the present invention having been devised, no completely satisfactory solution of this problem has been accomplished.

It is, therefore, an object of this invention to provide an improved regulator construction in which the tendency of the hairspring to foul or catch on the regulator-arm is entirely eliminated. To this end, an improved construction is provided in which the regulator-arm of the regulator is extended toward the balance-wheel at least as far as the adjacent face of the balance-wheel.

With the above and other objects in view, this invention includes the improved features and combinations of features disclosed in the following description, appended claims and accompanying drawing forming a part of this specification.

In the accompanying drawing, in which one way of carrying out the invention is shown for illustrative purposes:

Fig. 1 is a rear elevation of a movement of a time-instrument made in accordance with this invention;

Fig. 2 is an end elevation of Fig. 1;

Fig. 3 is a sectional view on line 3—3 of Fig. 1; and

Fig. 4 is a perspective view of a regulator made in accordance with the present invention.

Referring to the drawing, a movement 10 of an alarm clock is illustrated. This movement 10 comprises front and rear movement-plates 11 and 12 respectively joined by pillars 13 in a usual and well-known manner. The balance-wheel 14

55 is rigidly secured to a balance-staff 15, which

latter is pivotally mounted in pivot-bearings 16 and 17 in a usual manner. The balance-staff 15 carries the hairspring 18, which has one of its coils or turns 19 extending through a slot 20 of the regulator-arm or finger 21, which latter forms part of the regulator 22. The regulator-arm or finger 21 has an extension 23 which extends toward the balance-wheel at least as far as the plane of the adjacent face 24 of the balance-wheel 14, and preferably extends a substantial distance beyond the balance-wheel, as shown in Fig. 2.

In the constructions which have heretofore been devised, the regulator-arm has not extended as far as the plane of the adjacent face of the balance-wheel, in consequence of which the hairspring 18, which is exceedingly fine, flexible and composed of many coils or turns, has frequently had one or more of its coils fouled or caught over the ends of such regulators by passing between the end of the regulator and the adjacent face of the balance-wheel when the time-instrument has been subjected to a severe shock or jar sufficient to cause the hairspring-coils to surge or swing violently away from the plane they normally occupy, and down toward and into engagement with the face of the balance-wheel, as well as having a side-thrust action enabling them to pass between the balance-wheel and regulator-arm to hook over or foul upon the same.

After much difficulty and futile efforts to overcome this difficulty which has existed in the art for many years, applicant finally devised the apparently simple idea of extending the regulator-arm to a position at least to the plane of the adjacent face of the balance-wheel, so as to provide no space sufficient even for the fine hairspring 18 to get between the regulator-arm and the balance-wheel, thus providing a construction which has completely eliminated this troublesome difficulty.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. A time-instrument including: a pivotally-mounted balance-wheel; a hairspring operatively connected to said balance-wheel to oscillate the same; and a regulator mounted at one

side of said balance-wheel and having a regulator-arm adjustably engaging said hairspring; said regulator-arm having a free extension extending from the free end of the regulator-arm 5 and at least to the plane of the adjacent face of said balance-wheel so as to prevent fouling of the hairspring on the end of the regulator-arm or its extension.

2. A time-instrument including: a pivotally-mounted balance-wheel; a hairspring operatively connected to said balance-wheel to oscillate the same; and a regulator mounted at one side of said balance-wheel and having a regulator-arm adjustably engaging said hairspring; said regulator-arm having a free extension extending from the free end of the regulator-arm and at least to the plane of the adjacent face of said balance-wheel adjacent the periphery of the latter so as to prevent fouling of the hairspring 15 on the end of the regulator-arm or its extension.

3. A time-instrument including: a pivotally-mounted balance-wheel; a hairspring operative-

ly connected to said balance-wheel to oscillate the same; and a regulator mounted at one side of said balance-wheel and having a regulator-arm adjustably engaging said hairspring; said regulator-arm having a free extension extending from the free end of the arm away from the pivot axis and to and beyond the plane of the adjacent face of said balance-wheel so as to prevent fouling of the hairspring on the end of the regulator-arm or its extension.

4. A time-instrument including: a pivotally-mounted balance-wheel; a hairspring operatively connected to said balance-wheel to oscillate the same; and a regulator mounted at one side of said balance-wheel and having a regulator-arm adjustably engaging said hairspring; said regulator-arm having an extension extending to and beyond the plane of the adjacent face of said balance-wheel adjacent the periphery of the latter.

DUDLEY S. INGRAHAM.
